Primary Examiner — Vy N Koenig(74) *Attorney, Agent, or Firm* — Hedman & Costigan,
P.C.; James V. Costigan; Kathleen A. Costigan(57) **CLAIM**

I claim the ornamental design for a shower seat, as shown and described.

DESCRIPTION

FIG. 1 is a front perspective view of a shower seat showing my new design;

FIG. 2 is a front elevational view thereof;

FIG. 3 is a rear elevational view thereof;

FIG. 4 is a right side elevational view thereof;

FIG. 5 is a left side view thereof; and,

FIG. 6 is a top plan view thereof.
